UNITED STATES PATENT OFFICE.

FRANK C. RINSCHE, OF ST. LOUIS, MISSOURI, ASSIGNOR TO UNIVERSAL ACCOUNTANT MACHINE COMPANY, OF ST. LOUIS, MISSOURI, A CORPORATION OF MISSOURI.

COUNTING MECHANISM.

SPECIFICATION forming part of Letters Patent No. 723,213, dated March 17, 1903.

Application filed November 10, 1902. Serial No. 130,726. (No model.)

To all whom it may concern:

Be it known that I, FRANK C. RINSCHE, a citizen of the United States, residing at St. Louis, Missouri, have invented a certain new and useful Improvement in Counting Mechanisms, of which the following is a full, clear, and exact description, such as will enable others skilled in the art to which it appertains to make and use the same, reference being had to the accompanying drawings, forming part of this specification, in which—

Figure 1 is a front elevation. Fig. 2 is a side elevation. Fig. 3 is a rear elevation. Fig. 4 is a transverse sectional elevation viewed from the front. Fig. 5 is an elevation, partly in section, on the line 55 of Fig. 1. Fig. 6 is a fragmentary sectional view of the shaft and the setting-sleeve; and Fig. 7 is a view of said setting-sleeve looking at its inner end, the shaft being shown in section.

My invention relates to improvements in counting mechanisms and mechanisms of a like character, my objects being to provide a simple, compact, and inexpensive structure by means of which the various counting-disks are actuated at the proper intervals and to provide a simple and efficient means for resetting the mechanism.

To these ends and also to improve generally upon mechanisms of the character indicated, my invention consists in the various matters hereinafter described and claimed.

Referring now more particularly to the drawings, 1 indicates a shaft which is rotatably supported upon a suitable standard, here shown as having the side arms 2, in which said shaft is mounted. Loosely mounted upon the shaft are the counting wheels or disks 3 and 4, the disk 3 in the present instance being the units-disk and the disk 4 the tens-disk. Of course any suitable number of disks can be employed, but I have here illustrated only two. Each disk has suitably fixed thereto to rotate therewith a ratchet-disk 5, the said ratchet-disk connected to the units-disk or wheel being upon the outer side of the same—i. e., the side removed from the tens-disk—and the ratchet-plate for the tens-disk is upon the inner side

of said disk—i. e., the side adjacent the units-disk. These ratchet-disks are of course provided with the proper number of teeth. Secured to the units-disk to rotate therewith is what may be termed a “transfer-disk” 6, this transfer-disk being upon the inner side of the units-disk, and therefore being adjacent to the ratchet-disk upon the tens-wheel. The periphery of this transfer-disk lies in such a line that a pawl engaging the same and extending across the ratchet-disk of the tens-wheel is prevented from engaging with the teeth of said latter-mentioned disk; but said transfer-disk is provided with a single tooth or recess 7, which as the said transfer-disk is rotated is adapted to successively coincide with the teeth upon the ratchet-disk of the tens-wheel. A yoke hangs from the said shaft 1 and has side members 8 and 9 and a cross-bar 10 connecting the same, one of said side members (here the member 9) being extended to form an actuating arm or lever adapted to be engaged by a suitable part upon the element whose movements are to be counted, such element being here shown as a sprocket-disk A, provided with a pin a, adapted to engage the said actuating-arm for the purpose of moving the same. Pivotedly supported upon a suitable intermediate cross-bar 11 of the said yoke are pawls 12 and 13, the pawl 12 coöperating with the ratchet-disk 8 upon the units-wheel and the pawl 13 coöperating with the ratchet-disk upon the tens-wheel and being of a width to enable it to simultaneously engage both the ratchet-disk of the tens-wheel and the before-mentioned transfer-disk. Suitable springs 14 serve to yieldingly hold the said pawls against the disks in a well-understood manner. A suitable spring 15, connected to the actuating-arm 9 and to the said standard, tends to throw forwardly said actuating-arm and the parts connected thereto in order to effect counting operation of the mechanism, said actuating-arm being moved backwardly against the force of the said spring 15 by means of the pin a upon the movable element A, whose movements are to be counted. Retaining-pawls 16, mounted upon the standard, coöperate

with the ratchet-disks in a well-understood manner for well-understood purposes, these pawls being yieldingly held in engagement with said disks by means of springs 17.

5 Manifestly the pawls 12 and 13 move with the swinging yoke, and each time that said yoke moves forwardly the pawl 12 moves the units-wheel through one-tenth of its revolution, the said pawl 12 engaging a new tooth each 10 time that the said yoke returns to its retracted or backward position. The transfer-disk is so set with relation to the units-disk that during the first nine forward movements of the swinging yoke the pawl 13 merely rides 15 idly upon the periphery of said transfer-disk, and therefore does not operatively engage the ratchet-disk of the tens-wheel. Upon the ninth movement of the units-disk, however, the tooth or depression 7 of the transfer- 20 disk is brought into coincidence with the tooth of the ratchet-disk of the tens-wheel, which lies in position to be engaged by the pawl 13 as the swinging yoke returns after its ninth forward movement. When, therefore, 25 the said yoke makes its tenth forward movement, the pawl 13 engages the ratchet-disk of the tens-wheel and advances said wheel one step, the tens-wheel and the units-wheel moving through this one step together.

30 The transfer-disk is therefore advanced during the movement of the tens-wheel just described, so that the tooth or depression 7 of the said transfer-disk is carried beyond the point at which it is adapted to receive the 35 pawl 13 in the movement of the swinging yoke, and through the next nine movements of the yoke and the units-wheel the pawl 13 merely rides idly upon the periphery of the transfer-disk, as heretofore described.

40 While I have here shown only two counting or numbering wheels, it will be apparent that any number of said wheels can be employed, each wheel except the last or highest in the series being provided with a transfer-disk 45 upon its side adjacent the wheel of next higher value and each wheel except that of the lowest value being provided with a ratchet-disk upon its side adjacent the wheel of next lower value.

50 The means for resetting the mechanism is now to be considered. The shaft 1 has an angular slot 18, and connected to each counting-disk is a pawl 19, which when the wheels are at zero lies in said slot with its end so engaged 55 by a wall of the said slot that when the shaft is turned in the direction corresponding to that in which the said wheels are driven the wheels will be moved by the shaft. During the movement of the wheels under the action 60 of the actuating-arm 9 the pawls merely ride upon the outer surface of the shaft, said pawls being preferably held in engagement with the shaft by means of springs 20. Slidably mounted upon the end of the shaft which 65 projects beyond the standard is a sleeve 21, which is provided with a pin 22, which en-

ters the said angular slot 18, so that the sleeve is guided in its sliding movements and the sleeve and shaft are connected to rotate together. The sleeve is provided upon its inner end with a notch 23, which has upon one side a substantially straight wall, producing a shoulder 24, and has a sloping wall or cam-surface 25 upon its other side. A pin 26 upon the standard or any other suitable relatively fixed member enters the said notch. The sleeve 21 is yieldingly held in innermost position—*i. e.*, with the pin 26 in the notch 23—as by means of a spring 27, coiled about the shaft and bearing between the said sleeve and the head 28 of the shaft. Normally the parts are in the positions indicated in the drawings, with the sleeve in its innermost position and the pin 26 against the shoulder 24, whereby movement of the shaft 1 in the direction of 75 rotation of the counting-wheels is prevented. As the counting-wheels are actuated by the pawls 12 and 13 they move freely about the said shaft, the pawls 19 riding idly about the shaft and assuming any necessary positions. 80 When, however, it is desired to reset the counting-wheels, the sleeve 21 is pulled outwardly to carry the shoulder 24 clear of the stop or pin 26 and is then turned toward the right through a complete revolution, the operator relaxing the outward tension upon the sleeve after the said shoulder has been moved past the said pin, whereby as the sleeve completes its rotation the cam-surface 25 permits the same to gradually move toward innermost position, with the pin in the notch 23 and against the said shoulder 24. During 90 the rotation of the shaft the groove 18 receives the free ends of the various pawls, and after a pawl is thus picked up by the shaft the 95 shaft through the pawl moves the counting-wheel, the various wheels being brought to zero as the shaft 1 comes to rest. 100

I am aware that minor changes in the construction, arrangement, and combination of 110 the several parts of my device can be made and substituted for those herein shown and described without in the least departing from the nature and principle of my invention.

Having thus described my invention, what 115 I claim as new, and desire to secure by Letters Patent, is—

The combination with a supporting-bracket, of a grooved shaft mounted therein, a spring-pressed sleeve slidably mounted upon said 120 shaft, means for preventing independent rotation of said sleeve and shaft, means on the bracket-support and sleeve for locking the sleeve against movement and determining its own position and also the zero position of the 125 shaft, units and tens indicating wheels loosely mounted on the shaft, pawls on said wheels adapted to enter the groove in the shaft, ratchet-wheels conjoined to said units and tens indicating wheels, a notched transfer-disk carried by the units-wheel, a yoke suspended from the shaft and carrying pawls, 130

one of which coöperates with the ratchet-wheel of the units-indicator and the other of which coöperates with the transfer-disk and the ratchet-wheel of the tens-indicator, and 5 means for vibrating said yoke; substantially as described.

In testimony whereof I hereunto affix my

signature, in the presence of two witnesses, this 6th day of November, 1902.

FRANK C. RINSCHE.
